(57) **CLAIM**

The ornamental design for a T-post puller, as shown and described.

DESCRIPTION

FIG. 1 is a front view of a T-post puller.

FIG. 2 is a right side view of the T-post puller.

FIG. 3 is a top end view of the T-post puller.

FIG. 4 is a bottom end view of the T-post puller.

FIG. 5 is a left side view of the T-post puller.

FIG. 6 is a bottom end view of the T-post puller; and,

FIG. 7 is a perspective view of the T-post puller with dash-dot-dot-dash lines indicating an environment within which the T-post puller is applied.
